UNITED STATES PATENT OFFICE

136,460

DESIGN FOR A VEST OR SIMILAR ARTICLE

Benjamin Chalk, New York, N. Y.

Application June 26, 1943, Serial No. 110,536

Term of patent 3½ years

To all whom it may concern:

Be it known that I, Benjamin Chalk, a citizen of the United States of America, residing in New York city, county of New York and State of New York, have invented a new, original, and ornamental Design for a Vest or Similar Article, of which the following is a specification, reference being had to the accompanying drawing, forming part thereof.

Fig. 1 is a front view of a vest or similar article showing my new design.

Fig. 2 is a rear view thereof.

I claim:

The ornamental design for a vest or similar article, substantially as shown.

BENJAMIN CHALK.
